(57) **CLAIM**

The ornamental design for an acoustic foam sound reducer for vacuum power unit, as shown and described.

DESCRIPTION

FIG. 1 is a top perspective view of an acoustic foam sound reducer for vacuum power unit showing our new design; FIG. 2 is a top plan view thereof; FIG. 3 is a bottom plan view thereof; FIG. 4 is a front elevational view thereof; FIG. 5 is a rear elevational view thereof; FIG. 6 is a right side elevational view of FIG. 2; FIG. 7 is a left side elevational view of FIG. 2; and, FIG. 8 is a front elevational view thereof, showing the acoustic foam sound reducer located within a vacuum power unit, the unit being shown in broken lines for illustrative purposes only, forming no part of the claimed design.
